UNITED STATES PATENT OFFICE.

IGNATZ DANHEL, OF CHICAGO, ILLINOIS.

STOVE.

Application filed April 28, 1922. Serial No. 557,239.

To all whom it may concern:

Be it known that I, IGNATZ DANHEL, a citizen of the Republic of Czechoslovakia, residing at Chicago, in the county of Cook 5 and State of Illinois, have invented a new and useful Improvement in Stoves, of which the following is a specification.

This invention relates to improvements in stoves and has among its objects the provision of a stove construction whereby a maximum of heat generated therein will be conserved by preventing its escape into the chimney.

With these and other objects in view my 15 invention consists in the novel construction, combination and relative position of the parts and members hereinafter described and shown in the accompanying drawing, and particularly pointed out in the appended 20 claim.

Referring to the drawing in which like reference characters indicate like or corresponding parts:

Figure 1 is a front elevation of a stove 25 embodying my invention. Figure 2 is a cross section taken on line 2--2 of Figure 3, and Figure 3 is a vertical section taken on line 3--3 of Figure 1.

Referring to the drawing, the stove herein 30 illustrated as embodying my invention, comprises a base 10, a front wall 12, a rear wall 13, side walls 11, a bottom 14 and a top 15. Extending between the front wall 12 and rear wall 13, are the partition walls 16 which 35 extend from the top 15 downwardly to the ash pit 17. These walls 16 are slightly offset at 16^A to provide more room for the fire chamber 18 and magazine coal drum 21, and are provided with openings 16^B to permit the 40 passage of the smoke and hot gases into the gas chambers 19. The lower ends of these gas chambers 19 are provided with pivoted gates 25 which close these lower ends and afford a discharge gate for any accumulated 45 soot.

The fire chamber 18 is equipped with a grate 20, of any suitable construction, and

a magazine or coal drum 21, both of which obviously may be omitted when oil burners or the like are employed for heat generation. The fire door 22 provides access to the fire chamber, and the ash door 23 to the ash chamber pit. A suitable chute 24 with door 24^A may be provided for means of feeding coal to the magazine drum 21. The coal 50 reservoir is located between the partition walls 16 and is separated from the space above which serves as a gas mixing chamber 27, with a lateral wall 26 extending between the partition walls. The gas mixing chamber 27 has a gas deflecting wall 28 extending from the top 15 to a distance slightly below the flue opening 29.

As above stated, my object is to conserve and absorb the heat generated in the stove, 65 and to this end the construction above described and illustrated in the drawing, provides an indirect flow of the hot gases and smoke. From the illustrations it will be observed that the gases coming from fire 70 chamber 18 pass through the openings 16^B into the gas chambers 19 and pass up toward the top 15 and then through the openings 30 and then downwardly and under the wall 28 into the rear chamber 27^A and finally upwardly again into the flue. It is obvious that the heat in the discharged gases is to a great extent absorbed by the walls of the heater or 75 stove during its obstructed passage about the various walls.

I claim:

A stove comprising a fire chamber, a pair of parallel exhaust gas chambers, an exhaust gas mixing chamber above said fire chamber and between said parallel gas chambers, and a wall in said mixing chamber for deflecting the flow of the united exhaust gases into an opposite direction preliminary to their discharge from the stove.

In witness whereof, I have hereunto subscribed my name this 15th day of April, 1922.

IGNATZ DANHEL.
